STOP DEVICE FOR ROLLER SKATES

De Eldon E. Hayner, Floral Park, N. Y.

Application March 24, 1949, Serial No. 83,130

9 Claims. (Cl. 280—11.2)

1

This invention relates to roller skates, and in particular to a stop device applied to the toe portion of the skates to facilitate and increase the range of use of the skates in performance.

A particular object of the invention is to provide a flexible and adjustable stop means in which excessive wear on the rubber friction pad is prevented and one which will not mark the floor of the rink when the skater performs in gyrating motions with the stop in contact with the floor.

Other objects include the use of a stop of flexible nature which permits complete contact with the floor throughout the area of the stop so that a positive grip of the stop with the floor is afforded when the skater performs a jump or stop action; to provide for rotary adjustment of the stop so that the turning action thereof may be readily varied; to provide a stop device that can be applied to any roller skate; and to provide a device of the character referred to which offers a flexible, adjustable and firm stop to facilitate quick stops, jumps and spins.

With these and other objects in view, the invention comprises certain constructions herein-after described and then particularly pointed out in the claims, and a preferred embodiment of my invention is illustrated in the accompanying drawing in which:

Figure 1 is a view in side elevation showing the stop device as applied to the toe portion of a roller skate;

Figure 2 is a view in front elevation of the skate stop shown in Figure 1;

Figure 3 is an enlarged view, partly in section, of the stop as it appears on the skate in Figure 1;

Figure 4 is a section taken on the line 4—4 of Figure 3 and shows the mounting of the parts; and

Figure 5 is an enlarged side view of a stop device having variations of construction from the stop illustrated in Figure 1.

Referring to the drawing in detail, 10 indicates a roller skate body having the usual wheels 11 and wheel carriers 12. To the toe portion 13 of said body is attached, by any suitable means, a bracket 14 having an arcuately depending portion 15 slotted as at 16 to hold for adjustment, a stop assembly indicated generally by the numeral 17. The inner and outer faces of the segment 15 are corrugated as at 18 to fit like corrugations in the faces of an opposing limit nut 19 and a saddle ring 20 carried by a bolt 21 passing through said slot 16. The bolt also carries a lock nut 22 which coacts with the limit nut 19 through

ring 20 to permit radial or swinging adjustment of the stop with respect to the segment 15 and also raising or lowering movement of the stop with respect to the floor.

5 The stop 17 further consists of a cushion sleeve 23, made of rubber, plastic or any suitable material covered at its upper end by a cup disk 24 and supported at its lower end in a recess 25 formed in the face of an upper ball race plate

10 26. The latter is spaced from a lower ball race cup 27 by the ball or other roller bearings 28.

It is not essential to the invention that the anti-friction bearings be used, as plain plates or bearing disks having relative rotation can be employed if desired. The race cup 27 is shaped to provide a depending annular flange 28A from which prongs 29 are forced inwardly to be embedded in the rubber stop cushion 30 that is molded or otherwise secured in said cup. The top of the cup 27 is also shaped to provide inwardly directed

15 prongs 31 which coact with the prongs 29 to securely anchor the stop block or cushion in place in the cup. The cushion or rest 30 is provided with an axial recess 32 and a bore for passage of the bolt 21 which is provided with a slotted head 33 at the lower end and a thread at the upper end, the bolt passing through suitable

20 openings in the various parts of the stop structure to hold the latter assembled.

25 It is evident, by adjustment of the members 19, 20 and 22, that the bolt and its associated stop parts can be swung to any oblique position desired and that by longitudinal adjustment of the bolt itself the stop structure may be raised and lowered with respect to the skate.

30 In the modified form of the invention shown in Figure 5, the toe portion 35 of the skate body has secured thereto, as by screws 36 or the like, a bracket 37 having a base portion 38 and an

35 obliquely disposed tubular extension 39, in the threaded bore 40 of which is mounted for adjustment the threaded end of a bolt 41. The bolt mounts the stop parts including a lock nut 42, a cup disk 43, a cushion sleeve 44 interposed between the disk 43, and an upper ball race plate

45 45; and the rubber stop cushion 46 carried in the race cup 47. The cushion or stop block 46 has an axial cavity 48 in which the slotted head of the bolt is protected. In order to vary the angular position of the stop structure, use is made of a wedge block 49 of tapered shape which fits between the body of the skate and the face of the bracket 37.

50 The various adjustments may be accomplished by compression of the sleeves 23 or 44 under

pressure by tightening the bolt; by variation in the sizes of the sleeves used; by varying the sizes of the wedge blocks 49; and by relative adjustment of the bolt, lock nut and other associated parts.

It is evident, therefore, that I have provided a stop that can be attached to any skate or extension plate thereof, permits the rubber friction stop to make complete flat contact with the floor to give the skater a positive hold needed for a jump, stop or gyratory maneuver, prevents marking of the floor of the rink, and may be adjusted for rotary tension as the skater sees fit by the simple adjustment of the bolt. If desired, the bracket 14 may be made integral with the skate portion 13.

My invention is not to be restricted to the precise details of construction shown since various changes and modifications may be made therein without departing from the scope of the invention or sacrificing the advantages to be derived from its use.

What I claim is:

1. The combination with a skate, of a stop device including a bracket having a segmental portion for attachment to the toe portion of the skate, a floor engaging pad, means for pivotally mounting said pad, and means for adjusting said mounting means arcuately along said segmental portion.

2. The combination with a skate, of a stop device including a bracket for attachment to the toe portion of the skate, a floor engaging pad, means for pivotally mounting said pad, means for adjusting said mounting means obliquely, and means for adjusting said pad in a direction toward and away from the skate.

3. A skate stop device of the character set forth in claim 1 in which the pivotal mounting means includes a bolt, an anti-friction bearing supported on said bolt and means for securing the pad to said bearing.

4. A skate stop device of the character set forth in claim 1 in which the pivotal mounting means includes a bolt having a threaded portion, means for securing the bolt to the bracket, an

anti-friction bearing supported on said bolt, means for securing the pad to said bearing and means for varying the frictional resistance of said mounting means to pivotal movement.

5. A skate stop device of the character set forth in claim 2 in which said pad adjusting means includes a bolt, means for fixing said bolt in the bracket, a compressible member between the pad and said bolt fixing means and means for adjusting the bolt axially.

6. A skate stop device including a bracket for attachment to the toe portion of a skate, a bolt, means for securing the bolt to said bracket, a plurality of disks carried by said bolt, a plurality of pad members associated with said disks, one of said pads constituting a floor engaging stop and an anti-friction bearing between said disks.

7. A skate stop device including a slotted bracket, a bolt having a threaded end extending through said slot, lock means for securing the bolt to the bracket in adjusted position, a plurality of bearing disks on the bolt, a stop pad on one of said disks, anti-friction bearings between the disks and a yieldable cushioning means on said bolt between said bearing disks and said lock means.

8. The combination with a skate, of a stop device including a bracket, a bolt axially adjustable in said bracket, a floor engaging stop on the lower end of the bolt, means for revolvably mounting the stop on the bolt, and yieldable means for cushioning a movement of the stop along the bolt under floor engaging pressure.

9. In the combination set forth in claim 8 wherein said stop mounting means includes an anti-friction bearing and means for adjusting the bolt obliquely.

DE ELDON E. HAYNER.
